PHINEAS C. INGSTRUM, OF ROCHESTER, NEW YORK.

JOINTER-GUARD.

1,394,499.

Specification of Letters Patent.

Patented Oct. 18, 1921.

Application filed May 11, 1920. Serial No. 380,627.

To all whom it may concern:

Be it known that I, PHINEAS C. INGSTRUM, a citizen of the United States of America, residing at Rochester, in the county of Monroe and State of New York, have invented certain new and useful Improvements in Jointer-Guards, of which the following is a full, clear, and exact specification.

My invention relates to safety guards, and 10 more particularly to guards for woodworking machines, being designed to protect the hands of an operator of the machine; or others, from the cutting knives; and it has for its object to provide a guard which is adjustable to various sized machines; a further object is to provide a guard which projects a minimum distance from the frame of the machine, both beyond the front and above the table thereof. Another object is to provide a 20 guard, the parts of which are made interchangeable and adjustable relative to each other, so that parts may be used on machines having long or short cutting knives. A still further object is to provide a guard which 25 will always remain in its protective position, covering the cutting knives when the machine is at rest and operating, and one which will cover all of the knives which are not actually cutting the wood when the machine is 30 running, and a still further object is to provide a guard with a combined toggle arm and cam operating device, so that the guard will move with very little force applied through the work. To these and other ends the 35 invention resides in certain improvements and combinations of parts all as will be herein-after more fully described, the novel features being pointed out in the claims at the end of the specification.

40 In the drawings, in which like reference characters designate like parts throughout:

Figure 1 is a perspective view of a jointer guard constructed in accordance with and illustrating one embodiment of my invention;

45 Fig. 2 is a section through one section of the guard and base of the device shown in Fig. 1, showing how the parts telescope, parts being omitted for clearness;

50 Fig. 3 is a detail of the latch used on the same machine for holding the sections in the desired relation;

Fig. 4 is a perspective of another embodiment of my invention;

55 Fig. 5 is a side elevation of the guard shown in Fig. 4;

Fig. 6 is an end elevation showing a base equipped with wide tracks, a part being broken away; and

Fig. 7 is a bottom plan of the end section 60 of Fig. 1 on the single section of Fig. 4, illustrating the toggle arm which moves the guard.

In the drawings only such parts of the planer or jointer are shown as are necessary 65 to understand the relation between my guard and the machine on which it is mounted. In Fig. 1 a jointer having a wide work table 1 is shown with the usual adjustable gage 2. The cutting knives 3, which are shown in 70 dotted lines, Fig. 2, are mounted in a holder 4 which is rapidly revolved by a power driven shaft 5. To protect an operator's hands from these knives there is a guard, composed of telescoping sections 6, 7 and 8 in 75 the embodiment shown in Fig. 1 of the drawings. Sections 6 and 7 are provided with grooves 9 and 10 on the outside of downwardly extending flanges 11 and 12, these flanges also being provided on the inside with 80 ribs or tracks 13 and 14. The end section 8 has grooves 9 and 10 on the outside of flanges 11 and 12, but the inner tracks are omitted. These sections can slide, therefore, one on the 85 other, so that they are adjustable to vary the length of the entire guard between wide limits.

In order to hold the parts in the desired relation, so as to move as one unit, sections 7 and 8 are provided with a series of apertures 90 40. The ends of sections 6 and 7 are provided with spring latches 41 and 42 which are fastened to their respective sections with screws 43. The latch 41 is made of spring metal and has a turned up finger grip 44 on 95 the end and on the lower side carries a pin 45 adapted to fit in an aperture 40, as shown in Fig. 3.

Section 6 is mounted upon a base which consists of a casting 13 having rails or tracks 14' and 15 adapted to enter the slots or grooves 9 and 10 of section 6. Casting 13 is provided on one side with an ear 16 which forms a bearing to slide on a shaft 17, there being a set screw 18 to hold the parts in the 100 desired relation. Shaft 17 is supported in a two-way bearing 19 carried by a rod 20 permanently attached to the jointer at 21. A hand wheel 22 is provided in one side of the bearing 19 so that the bearing may be moved 105 to and from the jointer and easily adjusted as desired. A second set screw 23 on the bear-

- ing makes an additional vertical adjustment. It is obvious that hand wheels or other means may be used to hold these parts in the desired relation in the place of set screws, if desired.
- 5 In large guards, as shown in Fig. 1, it is better to have two supports, so on the opposite side casting 13 is provided with another ear (not shown) in which a rod 27 is mounted, there being a two-way bearing 29 sliding on 10 a rod or shaft 30 affixed to the jointer frame at 31. In this case the hand wheel 32 is on the side through which rod 27 passes, and the set screw 33 holds upon shaft 30. If desired, set screws 18 and the corresponding one 15 on the other side, which is not shown, may be set, and screws 23 and 33 loosened, so that hand wheels 22 and 32 will control the vertical and horizontal adjustments of the base. I have found in practice that this is sufficient 20 to hold the parts firmly. Casting 13 is also provided with a small roller or pulley 50 mounted so as to revolve freely, there being a weight 51 having attached thereto a cord 52, which, after passing over the roller, is attached to the end of the guard section 6 in 25 any suitable manner. The weight 51 is sufficient to cause the guard section 6 and, with it, sections 7 and 8, latched together as described, to move so that section 8 will contact with either the gage 2 or the lumber L, when it is passing over the knives for edging.
- To automatically move the guard back a sufficient distance for the lumber to pass, see Fig. 5, the end section 8 is provided on 30 its under side with a toggle arm 60, mounted to turn on a pivot 61 fastened to section 8, and held in a position to one side of the guard by a spring 62 attached to the toggle arm with a screw 63 and to the guard section 8 with a screw 63'. Toggle arm 60 has 35 a cam head 68 on its outer end, curved to form a lumber contacting projection. The downwardly extending flange 12 is cut away forming an opening 64 through which the toggle arm 60 passes, and also forming a stop 65, limiting its outward movement. One end of section 8 is cut away to form a cam 66, while the end 67 is flattened where it rests against the guard 2 on lumber L.
- 40 When a board L to be edged is moved along guard 2, it first strikes the cam head 68 of toggle arm 60, see Figs. 1 and 4. Continuing its movement the board, shown in dot and dash lines, Fig. 7 at L', causes 45 toggle arm 60 to move about its pivot 61, sliding guard 8 from the gage 2 until the position shown in L² is reached, just beyond which the cam surface 66 causes the section 8 to move still farther back (in practice this being only about one-sixteenth of an inch), thereby releasing the pressure on cam head 68, allowing toggle arm 60 to return to its initial position. It should be noted that there is no camming action of 50 board L upon head 68 until the guard has

been moved back the greater part of the necessary distance, so that the first part of the rearward movement of guard 8 is caused by toggle arm 60 rotating and at the same time pushing upon its pivot 61. By making the 70 cam head 68 long, boards of considerable width may be edged without adjusting the guard. This toggle arm action against the weight pressure works very smoothly and easily, much more power being obtained 75 through its use than when a cam surface alone is used, so that very little force is necessary to move these parts and, with them, the guard.

Where a long timber is to be edged, it 80 is sometimes desirable to lay the portion to be cut on the knives without running it through the machine, thereby first bringing one end into contact with lever 60. I, therefore, prefer to equip the end section 8 with 85 a cam plate 70 so that by lowering a plank upon the table 1 against gage 2 the guard 8 will be cammed against the weight action.

The guard may be left normally at a sufficient elevation from the table 1 for a board 90 B being planed to pass beneath, or may be adjusted for this purpose, according to the nature of the work.

In Fig. 4 I show my guard adapted for use on the smaller sized machines. Since 95 the base is similar to that shown in Fig. 1 excepting that a single support is used, and the guard is the same as section 8 of the guard in Fig. 1, the same reference characters are used.

I contemplate providing a guard with a series of sections, so that a section, when purchased, may be used for a small guard alone, or as a section of a large one. For 105 this purpose the base or casting 13, if desired, may be furnished in one size, with the rails 14' and 15' of various sizes to fit different width sections. Fig. 6 illustrates a base 13 with rails 14'' and 15' of sufficient width for section 8 of Fig. 1 to slide as a 110 one-section guard. Any combination desired can, therefore, be made up.

All of the guard sections are made with a curved, relatively smooth outside contour, so as to be close to the table 1 when adjusted 115 for edging lumber, and be of as little hindrance to the workmen as possible, while at the same time affording the greatest possible protection; the cutter being covered automatically all the time, either by the guard 120 or by the guard and lumber.

Having thus described my invention, what I claim as new and desire to secure by Letters Patent is:

1. In a machine having a rotary cutter 125 mounted on a table and projecting through a slot therein, the combination with a guard having a cam end and normally covering the slot, of a toggle arm pivoted to the guard, the toggle arm being adapted to move the 130

- guard as the work is fed toward the cutter into a position where the work will come in contact with the cam end on the guard.
2. In a machine having a cutter mounted on a table and operating through a slot therein, the combination with a guard normally covering the slot, the guard being slidably mounted relative to the table, a cam surface on one end of the guard, and a toggle arm pivoted to the guard, the toggle arm moving the guard by rotating about its pivot as it is engaged by work being fed to the cutter, and the guard cam completing the movement of the guard as the cam is engaged by the work. 70
3. In a machine having a cutter mounted on a table and projecting through a slot therein, the combination with a guard slidably mounted over the slot, and having a cam on its end, of a toggle arm pivoted to the guard, a spring for holding the toggle arm in one position, the toggle arm moving the guard a portion of its travel as work is fed to the cutter, the cam completing the travel of the guard, the toggle arm returning to its initial position as the cam receives the contact of the advancing work. 75
4. A knife guard for a jointer machine, comprising a base upon which a guard is slidably mounted, means tending to hold the guard over the knife, a toggle arm pivoted to the guard for moving it against the first mentioned moving means as work is fed toward the knife, and means carried by the guard for completing the movement of the guard started by the toggle arm. 80
5. In a machine having a knife mounted on a table and operating through a slot therein, and a work gage on the table, the combination of a guard adapted to slide over the slot, means for keeping one end of the guard against the gage, means for moving the guard from the gage as work is advanced to the knife comprising a toggle arm pivoted to the guard, and means on the guard to space the guard from the gage a distance equal to the width of the work being advanced to the knife. 85
6. In a machine having a knife mounted on a table and operating through a slot therein, and a work gage on the table, the combination of a guard adapted to slide over the slot, means for keeping one end of the guard against the gage, means for moving the guard from the gage as work is advanced to the knife comprising a toggle arm pivoted to the guard, the toggle arm being spring pressed into the path of work being advanced to the knife, means on the guard for spacing the toggle arm from the work, thereby allowing the toggle arm to return, impelled by the spring, into the path of the next piece of advancing work. 90
7. In a jointer guard, the combination with a base, a slot in the base, and a knife operating through the slot, of a slidable guard mounted above the knife, means for thrusting the guard across the knife, and a toggle arm for moving the guard against the guard moving means, said toggle arm being movable in one direction by a spring independent of the guard moving means. 95
8. In a jointer guard, the combination with a base, a slot in the base, and a knife operating through the slot, of a slidable guard to protect the knife, means normally tending to hold the guard across the knife, a toggle arm associated with the guard and movable with the guard in one direction and movable independent of the guard in the other direction. 100
9. In a jointer guard, the combination with a slidable guard mounted on a jointer machine, of a cam upon the end of the guard, a toggle arm pivoted to the guard normally extending to one side at an angle from the guard, the toggle arm moving the guard when lumber is brought into contact therewith until the toggle arm is substantially parallel to the guard, the guard cam then being contacted by the lumber to move the guard farther, permitting the lumber to pass. 105
10. In a machine having a rotary cutter mounted on a table and projecting through an opening therein, a guard normally covering the opening, the guard being mounted to slide relative to the table, a weight impelling the guard in one direction, a toggle arm pivoted to the guard having an operative and an inoperative position and having a work contacting head projecting forwardly from the end of one side of the guard, a spring for holding the guard in operative position, the guard being moved by the toggle arm when work engages the toggle arm, thereby rotating the toggle arm about its pivot into an inoperative position, the guard being engaged by the work and moved thereby so that the spring may return the toggle arm to its operative position. 110
11. In a machine having a rotary cutter mounted on a table and operating through a slot therein, of a guard normally covering the rotary cutter, a gage on the table, a slideway for the guard and means for keeping one end of the guard in contact with the gage, means for moving the guard from the gage, comprising a toggle arm pivoted to the guard extending normally at an angular relation thereto and projecting from one side of the guard near the gage, so that it will contact with work being advanced to the cutter across the table. 115
12. In a machine having a cutter mounted on a table and operating through a slot therein, of a guard movable over the cutter, means for holding the guard normally over the cutter, and means for moving the guard 120
- 130

against the first mentioned moving means, comprising a toggle arm pivoted to the guard at one end, and having a work contacting head on the other end projecting out from the guard at an angular relation there-
5 to, the toggle arm having an operative and an inoperative position with respect to said guard, so that as work is advanced to the cutter and is contacted with the work con-

tacting head, the angular relation between 10 the guard and toggle arm will decrease as the guard moves until the toggle arm becomes inoperative by the work passing the cutter.

Signed at Rochester, New York, this 7th 15 day of May, 1920.

PHINEAS C. INGSTRUM.
